UNITED STATES PATENT OFFICE.

ERNST HEUER, OF FORT WAYNE, INDIANA.

CROWN-SHEET OF STEAM-BOILERS.

SPECIFICATION forming part of Letters Patent No. 461,180, dated October 13, 1891.

Application filed June 8, 1891. Serial No. 395,559. (No model.)

To all whom it may concern:

Be it known that I, ERNST HEUER, a citizen of the United States, residing at Fort Wayne, in the county of Allen and State of Indiana, ⁵ have invented certain new and useful improvements in Crown-Sheets of Steam-Boilers; and I do hereby declare the following to be a full, clear, and exact description of the invention, such as will enable others skilled in the ¹⁰ art to which it appertains to make and use the same.

This invention relates to certain new and useful improvements in crown-sheets of steam-boilers, and especially to the manner ¹⁵ of fastening the bolts connecting the stay-bars to the crown-sheet; and it consists in the novel construction and arrangement of parts hereinafter fully described, and afterward pointed out in the claims, due reference being ²⁰ had to the accompanying drawings, forming a part of this specification, wherein—

Figure 1 is a side elevation showing the crown-sheet and the stay-bar in position thereon; Fig. 2, a similar view showing one ²⁵ of the plates composing the stay-bar removed, and Fig. 3 a vertical section taken on the line $x-x$, Fig. 1, and Fig. 4 a plan view of one of the plates composing the stay-bar.

Referring to the drawings, the letter A ³⁰ indicates the crown-sheet of a steam-boiler.

B indicates one of the stay-bars, consisting of two parallel plates $b-b$, having downwardly-curved ends $b'-b'$, the lower inner ends of which are curved, as at b^2-b^2 , to rest upon ³⁵ the upper curved edges of the crown-sheet, as shown.

C indicates bolts screw-threaded at their lower ends and flattened at their upper ends and perforated, as at c. Said bolts are tapped ⁴⁰ into the crown-sheet and so arranged that their flattened upper portions shall lie in the same longitudinal plane. The plates $b-b$, composing the stay-bar B, lie upon each side of the flattened ends of the bolts C and are ⁴⁵ perforated, as at b^3-b^4 , the perforations b^3 registering with the perforations c in the flattened ends of the bolts C, and through said perforations are passed headed pins D, perforated near their ends, as at d, and secured in

place by keys $d'-d'$. Through the perforations ⁵⁰ b^4 in the plates $c-c$ are passed bolts E, by means of which, and nuts e, the said plates are firmly bound together.

By employing the flattened bolts held in the stay-bars, as shown, said bolts and stay-bars are bound very rigidly to the crown-sheet and the bolts prevented from turning, it being impossible for the warping of the crown-sheet to displace or disturb the stay-bar ⁵⁵ and its fastenings. ⁶⁰

Having described my invention, what I claim is—

1. In a steam-boiler, the combination, with the crown-sheet, of stay-bars, each consisting of two arch-shaped plates resting upon the ⁶⁵ edges of the crown-sheet and united by bolts, and bolts tapped into said crown-sheet and flattened at their upper ends, said flattened ends being secured between the plates composing the stay-bar, substantially as described. ⁷⁰

2. In a steam-boiler, the combination, with the crown-sheet, of stay-bars, each consisting of two arch-shaped plates resting upon the edges of the crown-sheet and united by bolts, ⁷⁵ bolts tapped into said crown-sheet and flattened at their upper ends, and pins passing through the said flattened ends of the bolts and through the stay-bar and fastened by means of keys, substantially as described. ⁸⁰

3. The combination, with the crown-sheet A, of the stay-bars B, each consisting of the parallel arch-shaped plates $b-b$, having their lower inner ends curved, as at b^2-b^2 , to embrace the edges of the crown-sheet and united ⁸⁵ by bolts E, bolts C, tapped into the crown-sheet and flattened at their upper ends and embraced by the plates $c-c$, and pins D, passing through said plates and through the flattened ends of said bolts and fastened by keys ⁹⁰ d, substantially as shown and described.

In testimony whereof I affix my signature in presence of two witnesses.

ERNST HEUER.
